UNITED STATES PATENT OFFICE.

MOSES E. BLOOM, OF NEW YORK, N. Y.

ELEVATOR.

1,026,650.

Specification of Letters Patent. Patented May 21, 1912.

Application filed February 8, 1912. Serial No. 676,269.

To all whom it may concern:

Be it known that I, MOSES E. BLOOM, a citizen of the United States, and a resident of New York, in the county of New York 5 and State of New York, have invented certain new and useful Improvements in Elevators, of which the following is a specification.

My invention relates to elevators or hoists and its object is to provide a simple, efficient 10 and safe construction of apparatus whereby the car may be operated or its movements controlled through the medium of a screw shaft and a nut or nuts engaging said shaft, power being applied in the normal operation 15 of the apparatus to rotate the nut, as will be hereinafter more particularly described.

A further object of my invention is to permit the attendant on the car to raise or 20 lower the same in case of failure of the motive power or derangement of the mechanism by which the power is applied to the shaft.

To these ends my invention consists in the 25 novel constructions of apparatus and combinations of parts more particularly herein-after described and then specified in the claims.

In the accompanying drawings, Figure 1 30 is a general side elevation of an apparatus embodying my invention. Fig. 2 shows a portion of the same apparatus enlarged and in vertical section. Figs. 3 and 4 show the construction of the operating nuts employed 35 when my invention is carried out in the preferred way.

1 indicates the car of the elevator or hoist, which car moves in suitable guideways 2 in 40 the elevator well, as is usual in the art.

2 is a screw shaft connected to the car, preferably to the bottom of the same. When connected to the bottom, as shown, it depends from the floor of the car to any desired length, according to the extent of 45 travel of said car. At or near the bottom of the well in which the car travels is an operating nut 3 threaded to engage one of the threads upon the shaft 2, the latter being in the preferred construction of my 50 invention provided with the double or reversed threads shown, although it would be within my invention to dispense with one of said screw threads.

Bolted or otherwise secured to the floor 55 4 of the car is a bearing or socket 5 which

receives the upper end of the screw shaft and in which socket or bearing said shaft may turn should the emergency arise requiring that said shaft be turned by the attendant on the car in order to raise or 60 lower the latter. Normally, however, the shaft is held against rotation in said socket or bearing so that upon the application of power to the nut 3 rotating in its fixed bearing or support, said car will be caused 65 or permitted to rise or fall. When, however, the shaft is free to rotate in the bearing 5, it is then turned by the operator of the car. It is obvious that on rotation of said shaft by the operator of the car, the 70 nut 3 or other similar nut being at such time fixed, or held against rotation, the car will be caused to rise or fall depending upon the direction of rotation given to the shaft. To normally lock the said shaft 75 against rotation at its point of attachment to the car and to prevent it from becoming detached from its socket or bearing, the following or other suitable means may be 80 employed.

6 is a plate resting upon the flange which carries the hub 5 and provided with a boss or extension extending into the hollow shaft and fixed thereto by a pin 8 or other suitable means. The plate 6 is held normally 85 against rotation by means of pins 9 extending through the plate and into sockets or openings in the flange 5. When it is desired, however, to permit the shaft to rotate in its bearings 5, the pins 9 are removed so 90 that the plate 6 and attached parts may rotate freely, access being had to the pins 9 for this purpose through the cover 10 in the floor of the car, which covers the opening therein in which the plate 6 is mounted. 95 When free to rotate in the bearing 5 the shaft 2 may be rotated by the attendant on the car by manual or other power suitably applied to said shaft. As typical of means that may be employed for this purpose I 100 show a bevel wheel 12 keyed to the screw shaft 2, and a crank 13 mounted in suitable bearings on the side of the car and connected through a chain and sprocket wheels to a shaft 14 hung from the floor of the 105 car, and provided with a gear 15 engaging the bevel wheel 12. The nut 3 is mounted on suitable roller or other bearings on a fixed support, frame or boxing 16. The power to rotate said nut is applied from any 110

suitable source through shaft 17 or otherwise, said shaft being coupled, by means of suitable gear transmission, with gear wheel 18 on the periphery of said nut, as clearly shown. The power may be coupled and uncoupled from the nut if desired by means of a clutch 19 carried by the counter-shaft 20 and adapted to couple said shaft or uncouple it from the gear wheel 21 normally free on said shaft. These means for imparting rotation to the nut 3 or for controlling the application of power thereto are merely typical of a wide variety of devices, as well understood in the art, which may be employed for the same purpose.

It is obvious that the car may be raised or lowered when the screw shaft is fixed against rotation in its bearing or connection with the car by rotating nut 3 in one or 20 the other direction. In the preferred manner of carrying out my invention I employ a second nut 3' which has a thread the reverse of that for nut 3 and engaged with the reverse one of the two threads shown on 25 the shaft, so that by rotating the nut 3 the shaft may be raised, and by rotating the nut 3' in the same direction the shaft may be lowered, said nuts being operated in alternation and alternately coupled to the 30 counter-shaft 20 by the employment of the double cone clutch shown, which is provided for this purpose with a cone 19' governing the connection for shaft 20 with a second wheel 21' engaging the gear 18' on the periphery of nut 3'.

Inasmuch as the manner of controlling the application of the motive power to raise or lower the elevator by the attendant on the car is well understood in the art and 40 forms no particular part of my invention, the same is not shown. It is obvious, however, that with the special power controlling devices shown, a movement of the clutch in one direction from the neutral position shown will couple the power to the nut 3, leaving the nut 3' disconnected, and a movement in the opposite direction will couple nut 3' to the power, leaving nut 3 disconnected, thus permitting the car to be raised 45 or lowered at will.

In addition to the appliance described, I employ suitable means whereby either or both of the nuts 3, 3' may be locked against rotation, which device is especially desirable 55 when two nuts are employed and the power is applied through a clutch, which in its neutral position disconnects the power from both nuts. As typical of such a device for the nut 3 I show a pinion 22 adapted to be 60 shifted on shaft 23 into and out of gear with the gear 18 on nut 3, said pinion being locked against rotation when in gear by any means. A similar pinion 22' may be employed for the nut 3' and said pinions being rigidly connected on the same sleeve,

shiftable on shaft 23 by the arm 24, it is obvious that when both are engaged or in the position shown, neither nut can be turned; but either may be freed by operating the controlling lever 24, which however should stand in the position shown at the time when, in the operation of the clutches for the purpose of shifting the power from one nut to the other, the said clutches occupy a neutral position, in which neither clutch is connected to the power.

Any devices desired may be employed for controlling the movements of the locking devices and power clutch and operating them at the desired time.

The operation of the apparatus is as follows: Assuming that the power is connected to the nut 3, that the same is free from its locking device and free to rotate and that the screw shaft 2 is fixed in its bearing 5 on the car and incapable of rotation therein, the application of the power to the nut 3 will cause the car to rise or fall according to the direction of rotation of said nut and the direction of the thread of said shaft with which it engages. Assuming the one nut 3 only to be employed, it is obvious that the car may be raised or lowered by turning the nut 3 in one or the other direction. If all the devices shown be employed, however, and rotation of the nut 3 be effective in raising the car, it is only necessary to shift the power to the reversely threaded nut 3' engaged with the reverse thread on the shaft 2 in order to lower the car, said nut 3' being at such time freed from the control of the devices which may be employed to lock it against rotation.

In case of failure of the motive power or other derangement which would prevent the raising or lowering of the car by the operation of the nut or nuts, the car may be raised or lowered by the attendant by uncoupling the plate 6 fixed in the upper end of the shaft from the hub or bearing 5 so as to allow the shaft to rotate and then rotating shaft 14 and shaft 2, which may then turn in its bearing 5, and an operating nut, the latter being at such time fixed against rotation. Obviously, by rotating both the nuts at the same time oppositely to each other, they would coöperate to raise or lower the shaft.

What I claim as my invention is:

1. The combination substantially as described, of an elevator car, a screw shaft connected thereto and held against rotation in its bearing on said car, a nut mounted on a fixed bearing and engaging the thread of said shaft, means for rotating said nut, means for freeing the shaft to permit it to rotate in its bearing on the car and means on the car for rotating the same.

2. The combination with an elevator car, of a screw shaft depending therefrom, means for fixing it against rotation in its bearing

on the car or freeing it for rotation therein at will and means on the car for rotating said shaft when freed, as and for the purpose described.

5 3. In an elevator, the combination substantially as described, of a car, a screw shaft normally fixed against rotation and connected to the car, said shaft being provided with a pair of reversed threads, a pair 10 of correspondingly threaded nuts engaging said threads respectively, means for rotating one or the other of said nuts at will and means for locking both nuts against rotation.

15 4. The combination with an elevator car, of a double threaded screw shaft connected thereto, a pair of nuts, a motive power shaft, means for coupling the power to one or the other of said nuts at will and means for 20 locking both nuts when the power shifting appliance is in neutral position.

5. The combination with an elevator car, of a screw shaft connected thereto, means for fixing the same against rotation at its

point of connection with the car or freeing 25 it at will, a nut engaging said shaft and mounted on a fixed bearing, means for applying power to said nut, means for locking said nut against rotation and means on the car for rotating the shaft. 30

6. In an elevator, the combination substantially as described, of a car, a screw shaft normally fixed against rotation and connected to the car, said shaft being provided with a pair of reversed threads, and a 35 pair of correspondingly threaded nuts mounted on fixed bearings and engaging said threads respectively, said nuts being provided with means whereby they may be rotated to operate the shaft. 40

Signed at New York in the county of New York and State of New York this 3rd day of February A. D. 1912.

MOSES E. BLOOM.
